UNITED STATES PATENT OFFICE

ORRICK H. BIGGS, OF BEVERLY, MASSACHUSETTS, ASSIGNOR TO HYGRADE SYLVANIA CORPORATION, OF SALEM, MASSACHUSETTS, A CORPORATION OF MASSACHUSETTS

FLASH LAMP

Application filed May 27, 1931. Serial No. 540,272.

This invention relates to lamps of the type disclosed in the patent to Ostermeier No. 1,776,637, granted September 23, 1930, comprising an evacuated transparent envelope such as an ordinary light bulb containing flash material such as aluminum foil, oxygen (or oxygen-yielding material) to unite with the flash material in rapid combustion, and an igniter for starting the combustion.

10 While such lamps have marked advantages over prior photo-flash devices as heretofore constructed, they have the very serious disadvantage in that about one per thousand explodes when flashed, throwing the finely broken glass many feet and constituting a grave danger to the sight of those in the vicinity.

This invention involves the discovery that these explosions are due to leakage of air into the bulbs and/or to the leakage of combustible gas into the bulb from the cement used in mounting the base of the lamp on the bulb. Whereas an ordinary incandescent lamp and the like may be tested before use by lighting 25 the lamp, in the case of photo-flash lamps no practical way has as yet been found to test for accidental leakage during manufacture.

Heretofore these lamps have been manufactured with bakelite as the cement between the base and bulb, using alcohol as a softener for the bakelite. In the present methods of manufacture accidental leakage is most likely to occur in this region of the bulb, and in such cases I have found that alcohol vapor passes 30 into the bulb during the cementing process, thereby creating a condition which results in exceptionally violent explosions when the lamp is subsequently flashed.

Moreover, with a pressure of oxygen approximating 120-180 mm. hg., as these lamps have heretofore been manufactured, I have found that if air alone leaks into the bulb, an explosion of more or less violence depending upon the degree of leakage is likely to occur when the lamp is flashed. In general 45 the likelihood and/or violence of explosion, with the aforesaid pressure of oxygen, increases with increased air leakage up to an air pressure approximating that of the oxygen (approximately one-fifth atmosphere)

and then decreases with increased leakage. I believe that these explosions result from the expansion of the nitrogen and other inert gases in the air, and that the decrease in danger beyond the optimum air pressure of approximately one-fifth atmosphere is due to reduced rate of combustion resulting from retarded diffusion of the oxygen through the nitrogen.

Various attempts have been made to mitigate the danger of the aforesaid explosions but so far as I am aware they have not been successful. It has been proposed to increase the strength of the glass sufficiently to withstand the force of the explosive pressures: while the number of explosions may thus be reduced, those which do occur are correspondingly more violent; moreover this expedient reduces efficiency, due to decreased transparency, and increases the cost of manufacture. It has also been proposed to coat the inside of the glass bulb with a layer of cellulosic material such as parlodion: this not only decreases the efficiency and increases the cost but the bulbs are not as satisfactory in use.

In sharp contradistinction to these prior expedients to resist the explosive pressures, the present invention eliminates explosions by sealing each bulb to its base in such manner as to prevent the passage of much if any combustible gas into the bulb in case of leakage in the region of the base and by altering the contents of the bulb to prevent explosion irrespective of the amount of air leakage, that is, throughout the entire range of air pressures from zero to atmospheric pressure.

For the purpose of illustration, the single figure shows, in elevation, a typical photo-flash lamp comprising a bulb 1, a base 2, sealed to the bulb with intervening cement 3, flash material 4 such as aluminum foil, and an igniter 5.

In its preferred form, this invention involves the reduction of the oxygen pressure from approximately one-fifth atmosphere to a pressure of approximately one decimeter of mercury. This comparatively small reduction has the novel result of eliminating explosions due to air leakage, even in the region of one-fifth atmosphere of air where

the explosions occurred with greatest force in the prior tubes. I believe this result is due chiefly to a substantial decrease in the rate of diffusion of the oxygen through the 5 nitrogen to the coil owing to the decreased oxygen pressure, with a consequent reduction in the rate of combustion, resulting temperatures, and consequently of nitrogen expansion. In any event extensive tests show that 10 this slight decrease in the oxygen pressure substantially eliminates explosions due to air leakage.

While this reduction in oxygen pressure makes the flash somewhat slower, the same 15 amount of light may be obtained by using an envelope or bulb large enough to hold sufficient oxygen completely to oxidize the usual amount of flash material. Indeed it is unnecessary to increase the size of the bulb beyond the present standard (approximately 20 200 and 250 c.c.) unless more than the usual quantity (approximately 0.090 gms.) of flash material is used.

The novel function of the aforesaid reduction 25 in oxygen pressure may be made more apparent by contrasting it with a corresponding reduction in the quantity of flash material: while the former reduces the speed of flashing, it does not necessitate any decrease 30 in the total light, merely spreading the light over a longer period of time, whereas the latter would not only decrease the amount of light but it would have comparatively little tendency to avoid explosions inasmuch as it 35 would not affect the rate of combustion, nor the rate of nitrogen expansion.

Referring again to the drawing, the bulb 1 is customarily sealed to the base 2 with a cement 3 comprising bakelite softened with 40 alcohol which of course evaporates during the setting process. In case of incipient fracture at the base-end of the bulb, where fractures are most likely to develop in the process of sealing off the bulb, some of the alcohol vapor finds its way into the bulb during 45 the sealing process. This combustible vapor renders the bulb highly explosive, especially if some air has also leaked in as would ordinarily occur; and when the bulb is subsequently used for flash purposes it explodes 50 with violence.

According to the present invention this danger is eliminated by employing a cement, preferably a thermoplastic cement such as 55 bakelite, which is substantially free from combustible vapor in the sealing process, more particularly the bakelite is plasticized by holding it in suspension in a non-inflammable liquid such as glue, the preferred composition comprising:

100 gm. bakelite #6040... 57% gravimetric
25 gm. ground hard glue... 14% gravimetric
50 cc water..... 29% gravimetric

65 During the baking process after the mix-

ture is applied between bulb and base the glue breaks down and the bakelite serves as the permanent bond.

It should be understood that the present disclosure is for the purpose of illustration only and that this invention includes all modifications and equivalents which fall within the scope of the appended claims.

I claim:

1. A flash lamp comprising a transparent envelope containing flash material and oxygen at a pressure confined to approximately one decimeter of mercury.

2. A flash lamp of the type comprising a transparent envelope containing flash material in quantity sufficient, in relation to the strength of the envelope, to explode the envelope by rapid combustion in the presence of air at a pressure below atmospheric, the envelope also containing oxygen, characterized in that the pressure of the oxygen is too low to explode the envelope in the presence of air at any pressure below atmospheric.

3. A flash lamp comprising a transparent envelope having a capacity of the order of 200 to 250 cubic centimeters, at least approximately one-tenth gram of flash material, and oxygen at a pressure of approximately one decimeter of mercury.

Signed by me at Salem, Massachusetts, this 25th day of May 1931.

ORRICK H. BIGGS.
